UNITED STATES PATENT OFFICE.

WILLIAM H. SHICK, OF READING, PENNSYLVANIA, ASSIGNOR TO THE READING STOVE WORKS, ORR, PAINTER & CO., OF SAME PLACE.

DESIGN FOR A HEATER ATTACHMENT.

SPECIFICATION forming part of Design No. 30,906, dated May 30, 1899.

Application filed May 3, 1899. Serial No. 715,490. Term of patent 7 years.

To all whom it may concern:

Be it known that I, WILLIAM H. SHICK, a citizen of the United States of America, and a resident of Reading, in the county of Berks and State of Pennsylvania, have invented a certain new and original Design for a Heater Attachment, of which the following is a specification.

My design relates to a heater attachment for supplying air to the combustion-chamber of a heater or stove for the purpose of effecting a more perfect combustion of the generated gases.

Figure 1 is a plan view of a heater attachment, showing my design; and Fig. 2 is an elevation or edge view of the same.

As shown in the drawings, the leading features of my design are comprised in a tubu-

lar air-conduit having a straight air-inlet end *a* and a main portion *b*, bent, as shown, to conform with the inner wall of the combustion-chamber, to which it is attachable, and provided with a series of exit-openings *d* through its inner wall *c*, converging toward the center of the bend, the main portion *b* being of tubular cross-section, as shown at *e*.

What I claim is—

The design for a heater attachment substantially as shown and described.

Signed by me, at Reading, Pennsylvania, this 25th day of April, 1899.

WM. H. SHICK.
